(57) **CLAIM**

I claim the ornamental design for the automobile spring shade, as shown and described.

DESCRIPTION

FIG. 1 is a front view of the automobile spring shade lined for the color silver.

FIG. 2 is a rear view of the automobile spring shade lined for the color black.

FIG. 3 is a top view of the shade shown in FIG. 1.

FIG. 4 is a bottom view of the shade shown in FIG. 1.

FIG. 5 is a left side view of the shade shown in FIG. 1.

FIG. 6 is a right side view of the shade shown in FIG. 1.

FIG. 7 is a front view of the automobile spring shade of FIG. 1 shown in extended position and lined for the color silver.

FIG. 8 is a rear of the automobile spring shade of FIG. 2 shown in extended position and lined for the color black.

FIG. 9 is a top view of the shade shown in FIG. 7.

FIG. 10 is a bottom view of the shade shown in FIG. 7.

FIG. 11 is a left side view of the shade shown in FIG. 7; and, FIG. 12 is a right side view of the shade shown in FIG. 7. The broken line circles in FIGS. 1, 2, 7 and 9 represent surface ornamentation.
